UNITED STATES PATENT OFFICE.

EMIL FOX, OF NEW YORK, N. Y.

DESIGN FOR A BAS-RELIEF OF GENERAL GRANT.

SPECIFICATION forming part of Design No. 16,257, dated September 22, 1885.

Application filed July 21, 1885. Term of patent 3½ years.

To all whom it may concern:

Be it known that I, EMIL FOX, of the city, county, and State of New York, have invented a new and original Design for a Picture of General Grant in Bas-Relief, of which the following is a specification.

Reference is to be had to the accompanying photograph, forming a part of this specification.

10 The leading feature of my design consists in the picture of General Grant sitting in a chair, with his left arm resting on a carved arm of the chair and his right arm resting on a pedestal, with an ornamental paneled background in relief.

15 The picture represents the General as sitting in a chair, with his left arm resting on the carved arm of the chair, and with his right arm resting on a pedestal. The background 20 of the picture is an ornamental paneling, and the picture is surrounded with a frame ornamented with scroll-work. In the centers of

each side bar of this frame is the representation of two crossed cannons, and in the center of the bottom bar of the frame is an ornament 25 representing two cannons, a number of flags, two guns and bayonets, and a group of cannon-balls. Above the top bar of the frame is an ornament in leaf and scroll work, surmounted by an eagle with open wings, and a United 30 States shield on the front of its body.

I claim—

The design for a picture of General Grant in relief herein shown and described, the same consisting of the representation of General Grant sitting in a chair, with his left arm resting on a carved arm of the chair and his right arm resting on a pedestal, with an ornamental paneled background in relief.

EMIL FOX.
